UNITED STATES PATENT OFFICE.

SAMUEL H. TERRY, OF GUTHRIE, MISSOURI.

CAR-BRAKE.

SPECIFICATION forming part of Letters Patent No. 258,956, dated June 6, 1882.

Application filed February 21, 1882. (No model.)

To all whom it may concern:

Be it known that I, SAMUEL H. TERRY, residing at Guthrie, in the county of Callaway and State of Missouri, and a citizen of the United States, have invented new and useful Improvements in Automatic Car-Brakes, of which the following is a full description, reference being had to the accompanying drawings, in which—

10 Figure 1 is a front elevation of one end of a platform-car; Fig. 2, an under or bottom view; Fig. 3, a similar view of the draw-bar; Fig. 4, a cross-section on line $\alpha\alpha$ of Fig. 2.

The object of this invention is to provide a car-brake which shall be to a certain extent self-acting, and which will be operated by means of pressure on the outer ends of the draw-bars, either by reversing the engine or so far braking it that the momentum of each car 20 will furnish sufficient pressure at its draw-bar to operate the brake; and its nature consists in providing a spring draw-bar with a hinged section which may be moved to one or both sides of its direct line; in providing it with springs for returning the hinged section to its proper line; in providing the axle of one pair of wheels in one or both trucks of the car with a worm or scroll; in connecting the brake-chain with a pivot-bar formed or bent to be operated by the rear end or cross-head of the draw-bar; in providing the hinged section of the draw-bar with side springs to return it to a central position, and in the several parts and combinations of parts hereinafter described and claimed as new.

In the drawings, A indicates the platform; B, the wheels; C, the track or rails; D, the draw-bar; D', the hinged section of the draw-bar; E, the mainspring of the draw-bar; F, 40 the pivoted lever or bar for operating the chain; G, the cross-bar or bridge for supporting the rear end of the draw-bar; H, brake-bars; I I', chains for connecting the proper devices with the brake; a, the worm or scroll on the axle; b, the projection or point on the section D' of the draw-bar; c, side springs for the hinged section of the draw-bar; d, the joint in the draw-bar; e, beveled projection on the under side of the section D' for holding the section in position 50 when moved to one or the other sides of its straight line; f, the cross-head or rear end of

section D'; g, a pin on the cross-head f; h, rear, and i front bars of the pivoted lever F; j, notches in the support or bridge G with which the projection or flange e engages; k, 55 55 brake-lever; n, hangers for the brake-bar.

The part A is represented in the drawings as a platform-car; but it will be understood that it may equally well represent the bed or bottom of a freight, box, or other car or coach 60 used on railways.

The wheels B are of the ordinary construction and are placed upon an ordinary axlē. As shown, these wheels are connected with the car-body by brackets or standards, which are 65 such as are used in straight cars; but I propose to use trucks and support the body of the car upon the truck and hold it by king-bolts in the usual manner, as my devices and improvements are designed to operate in any 70 of the known forms of trucks used for supporting and carrying car-bodies.

The track C is the ordinary railway-track.

The draw-bar D is provided at its outer end with the ordinary mouth or head for receiving 75 coupling-links or other coupling devices, and it is supported in place in the usual manner. In some forms of draw-bars they are already provided with springs, which, if they have sufficient movement, may be used in the place 80 of the spring E, which spring, as shown, has a tendency to return the draw-bar to its extreme outward position after any compressing-pressure has been removed, which is the reverse of the action of springs ordinarily applied to draw-bars.

At the rear or inner end of the draw-bar I hinge the section D' by the hinge d. This hinged section is provided on its under side with a pin, b, which extends low enough to 90 connect with the scroll a of the axle. It is also provided with a flange or short projection, e, which is beveled at its back end, so as to easily pass over the support or bridge G, and in order to have it return to its middle position when free from the action of the scroll a or the flange e, I have provided side springs, c, which may be connected with the main draw-bar, as shown in Fig. 2, or with the truck or body of the car, as shown in Fig. 3.

I provide one axle of the truck with the scroll or worm a, which is best made by cast-

ing the worm or scroll with a collar sufficiently large to slip over and be keyed or screwed to the axle. The lever or frame F is so formed or bent that when the head *f* of the section D' 5 strikes either end of the lever or frame F it will move the end of the latter forward, while the bar *i* of the lever F is so formed as to bring the lever or pivot bar to its proper position when the draw-bar is returned. The chains 10 I I' are connected with this lever or frame F, and receive their movement therefrom, the chain being firmly connected with the brake-bar H. A movement of either end of the lever F will set the brake.

15 In operation, when power is applied to the outer end of the draw-bar, either by the reverse action of the engine or the momentum of the cars, the spring E is compressed, and this backward movement of the draw-bar brings the 20 pin or flange *b* into contact with the scroll or worm *a*, when the rotation of the scroll will throw the hinged section D' to one side or the other, according to the direction in which the wheels are rotated, and when so thrown to one 25 side the flange *e* engages with the notches *j*, (shown at Fig. 4,) which notches or guides are so located as to just free the pin *b* from the ends of the scroll, and they also hold the section D' off at the side, and will hold the brake 30 as long as the flanges *e* remain in the notches. When the pressure is removed a slight jar will throw the flanges *e* out of the notches or bearings in the frame G, and the spring E will throw the draw-bar D D' so far forward as to 35 bring the pin *b* out of range of the scroll, when the side springs, *c*, will return the section D' to its middle position or line. The moving backward of either end of the bar or frame F communicates the motion through the chain or 40 chains I to the brake-bar or brake-lever, and sets the brakes; and as this brake is designed to be applied in the main to freight-cars and freight-trains it will be found a very efficient aid to the engineer in controlling his train, 45 and it may be worked in connection with the ordinary shaft or hand-wheel, or without it, as desired.

In backing a train by the engine, the first movement throws the draw-bar and its hinged 50 section straight back, in which position it remains until the wheels commence moving, when the movement of the wheels will throw the head *f* over toward the side *i'* of the lever or frame F, in which position it will remain as long as 55 the reverse movement is continued, and the

only effect it has in case it turns the frame-lever F is to slacken the chain I, for it will be understood that in braking either a double or single lever brake the chain I' is not used, and in order to set the brakes when the train is 60 backed sufficiently far, the draw of the engine will cause the pin *g* to come in contact with the inner bar, *i*, and the point *i'*, which causes the frame F to move in the same direction that the push on the opposite side gives it, and again 65 sets the brake, so that the brake can be made to operate when the car is moving in either direction.

It will also be understood that the side springs, 70 *c*, are not of sufficient strength to move the pivoted section of the draw-bar while braking the cars; but as soon as the brakes are released then they will throw the section again to its middle position, or in line.

What I claim as new, and desire to secure by 75 Letters Patent, is as follows:

1. The scroll *a*, attached to a car-axle, in combination, with the hinged section or prolongation D' of the draw-bar, having the projection or pin *b*, substantially as specified. 80

2. The pivoted lever or frame F, composed of the bars *h i*, in combination with the cross-head *f* of the bar D', substantially as described.

3. The combination of the bar D', having the flange or projection *e*, with the guide-bridge G 85 and the head *f*, with the pivoted lever or frame F, substantially as set forth.

4. The combination of the pivoted sliding bar D', having the projection or pin *b* and head *f*, with the pivoted frame F and brake-operating chain I, substantially as specified. 90

5. The side springs, *c*, in combination with a sliding draw-bar, D, having a pivoted section, D', for setting the pivoted section when moved out of line, substantially as described. 95

6. The combination of the sliding draw-bar D, spring E, pivoted section D', pin *b*, and scroll *a*, with the pivoted lever or frame F, and the brake-operating chain I, substantially as set forth. 100

7. The pivoted frame F, having the bar *i*, with its bend or stop *i'*, in combination with the head *f* of the bar D', and the pin *g*, whereby the brake can be operated by pulling on the draw-bar, substantially as specified.
